UNITED STATES PATENT OFFICE

THOMAS UTLEY, OF WEST DERBY, LIVERPOOL, ENGLAND

SLIDABLE WINDOW OR THE LIKE

Application filed September 7, 1929, Serial No. 390,972, and in Great Britain September 15, 1928.

This invention relates to slidable windows or the like, particularly but not exclusively for use on ships and has special reference to the type of slidable window wherein a glass holder is adapted to be slidably moved in a fixed frame by hand operated gearing and is provided with projections or cams that enable it to be moved away from its seating in the fixed frame so that it can then be slidably moved without friction and its seating face which is usually provided with a rubber ring that can be pressed against the fixed frame to provide a water-tight joint.

The chief object of the present invention is to simplify the construction of the slidable window and to enable the glass to be readily removed from the glass holder in the case of breakage for instance, and replaced without completely dismantling the window.

According to this invention the fixed frame is provided with side grooves to receive lateral projections on the slidable glass holder which at its inner part or face is provided with means, for example, projections or cams such as those aforesaid, to enable the glass holder to be moved and held away from its seating when it is slidably moved. The said projection or cams which engage with recesses or grooves on the inner face of fixed frame when the window is closed, may be provided on a retaining ring, which in conjunction with a flange on the glass holder serves to retain the glass in the holder. When it is desired to open the window, for example by operating gearing such as that aforesaid, the glass holder, as it tends to be drawn downwardly, is first moved away from its seating by the projections or cams engaging with bevelled or curved ends of the said recesses or grooves and after the projections or cams have moved out of the recesses they bear against the inner faces of the fixed frame and thus maintain the glass holder with its rubber seating ring out of engagement with the seating in the fixed frame, at the same time providing a metal to metal contact which facilitates the sliding movement of the glass-holder. The said retaining ring may be secured to the glass holder in a readily de-

tachable manner so that after removing the same, the glass can be quickly taken out of the glass holder.

In order that the said invention may be clearly understood and readily carried into effect, the same will now be described more fully with reference to the accompanying drawings, in which:—

Figure 1 is a front view of one construction of the improved sliding window for use on ships.

Figure 2 is a vertical sectional view taken on the line 2—2 of Figure 1.

Figure 3 is a transverse sectional view taken on the line 3—3 of Figure 1.

Figure 4 is a side view of part of the window.

Figures 5 and 6 are enlarged fragmentary sectional views showing the glass holder in the closed position and in an open position respectively.

Figures 7 and 8 are enlarged fragmentary side views showing the glass holder in the positions shown in Figures 5 and 6.

Figures 9 and 10 are enlarged cross sectional views also showing the glass holder in the positions shown in Figures 5 and 6.

A represents the main or fixed frame which may be of any usual or suitable construction and which is provided with side grooves A¹ in the part that receives the glass holder. B represents the glass holder which is provided at its sides with projections B¹ that are disposed in the aforesaid side grooves A¹ in the frame A. The glass plate B² is retained in the glass holder against a flange B³ by means of a retaining ring C which is detachably secured to the glass holder by a number of screws C¹ (see Figures 1 and 2) and which extends beyond the inner face or sides of the fixed frame as shown. Around the outer surface of the glass holder a rubber seating ring D is provided and this is adapted to be pressed against a seating face A² on the fixed frame so as to make a water-tight closure, by means of retaining screws E that are mounted in lugs E¹ and are adapted to bear on the inner surface of the glass holder. The construction is such that limited movement of

the glass holder B with its seating ring D towards and away from the seating A² on the frame A is permitted. The retaining ring C extends outwardly beyond the glass holder and the extending portions are provided with a number of projections or cams F which fit in recesses or grooves G in the sides of the fixed frame when the glass holder is in the closed position, the projections or cams being such that they can be moved out of the recesses or grooves G when the glass holder is moved away from its seating A² in the fixed frame. At the lower part of the frame A gearing is provided for slidably moving the glass holder, which latter is loosely connected by a pin and slot H to a nut or block I threaded on a main operating screw J that can be rotated by hand operated bevel gearing K. In order to enable the sliding window to be opened, the aforesaid retaining screws E are first manipulated to release the pressure on the glass holder B and the rubber seating ring D. The main operating screw J is then rotated by the bevel gearing K so as to cause the nut or block I to be axially moved. Owing to the projections or cams F on the retaining ring C of the glass holder, engaging with bevelled or rounded surfaces at the lower ends of the aforesaid recesses or grooves C they are positively moved out of the recesses so as to travel on the inner faces of the sides of the fixed frame. This movement results in the rubber seating ring D being moved definitely out of contact with the seating A² on the fixed frame to eliminate friction so that the sliding movement of the glass holder can be effected whilst it is maintained in this position by the projections or cams engaging with the inner faces of the fixed frame, and providing a metal to metal contact that facilitates the sliding movement. The glass holder may be secured in any desired open position by means of the aforesaid retaining screws E bearing against the outer surface of the retaining ring so as to clamp the glass holder against the fixed frame. When it is desired to close the window the aforesaid gearing is operated in the reverse direction in order to raise the glass holder, which on being fully raised can be pressed by the retaining screws E so that its rubber seating ring bears against the seating A² in the fixed frame, this being permitted by the projection of cams F fitting in the recesses or grooves G. In order to enable the glass to be taken out of the glass holder, it is merely necessary to remove or displace the lugs E¹ carrying the retaining screws E and to take off the retaining ring after unscrewing the screws C¹ thus leaving the glass free to be removed. A new glass plate can then be placed in the glass holder and held therein by screwing the retaining frame into position, whereupon the lugs E¹

carrying the retaining screws E can be positioned for enabling the latter to bear on the glass holder as required.

What I claim and desire to secure by Letters Patent of the United States is:—

1. A slidable window of the type referred to, comprising a fixed frame having interior side grooves, a glass holder having lateral flanges fitted to slide in said grooves, means for slidably moving the holder in said grooves, and projections on the holder cooperating with the fixed frame while moving thereover, as the holder slides in the grooves, for positively moving the holder away from the fixed frame.

2. A slidable window of the type referred to, comprising a fixed frame having interior side grooves, a glass holder having lateral flanges fitting in said grooves, means for slidably moving the holder in the grooves of the fixed frame, a retaining rim on the holder for holding a glass in position therein, said rim extending laterally beyond the sides of the holder and having means projecting from one face and engaging inboard surfaces of the fixed frame while moving thereover during said sliding movement, to positively move the holder from the fixed frame.

3. A slidable window of the type referred to, comprising a fixed frame having interior side grooves, a glass holder fitting in said grooves, a rubber seating ring between the glass holder and said frame, means for slidably moving the holder in said grooves, and cam members on said holder cooperating with recessed walls of the grooves of the fixed frame to force the holder away from the frame and relieve the pressure on the rubber seating ring as said holder slides in the frame.

THOMAS UTLEY.
